UNITED STATES PATENT OFFICE.

ERNST BOLEY, OF CLEVELAND, OHIO, ASSIGNOR TO THE AMERICAN STEEL AND WIRE COMPANY OF NEW JERSEY, A CORPORATION OF NEW JERSEY.

METHOD OF CONTINUOUSLY CLEANING AND DRAWING WIRE.

Application filed December 27, 1920. Serial No. 433,281.

To all whom it may concern:

Be it known that I, ERNST BOLEY, a citizen of the United States, and resident of Cleveland, in the county of Cuyahoga and State of Ohio, have invented a certain new and useful Method of Continuously Cleaning and Drawing Wire, of which the following is a specification.

This invention relates to the manufacture of wire, and more particularly relates to the cleaning and drawing methods used in making wire from bundles of hot rolled rods.

In existing methods of making wire from rolled rods, which are received from the rolling mill in coils or bundles weighing from 150 up to 300 pounds or more, the rods, when received at the cleaning house, are covered with a coating of iron oxid or scale which must be removed preparatory to commencing the reduction of the rods into wire by the drawing thereof through one or more dies.

After reaching the cleaning house a considerable number of bundles of rods are placed on a rack or "pin", (a device used in handling the bundled rods in the cleaning house) and are conveyed thereon, either manually or mechanically, to a pickling vat which contains a heated solution of sulfuric acid.

The pin with its load of bundles is then lowered into the pickling vat, the rods being immersed in the dilute sulfuric acid forming the pickling solution, standing therein for twenty to thirty minutes.

The acid solution in the vat attacks the scale on the surfaces of the rods so as to loosen and dissolve the coating of scale and clean the bundles of rods while they are in the vat.

The pin with its load of pickled rods is then removed from the vat to a water vat, and is dipped therein to remove any free acid clinging to the cleaned surfaces of the bundles.

After being washed in this manner, the bundle laden pin is removed and transferred to a "sulling" rack where the bundles of rods on the pin are placed under a water spray and remain for from fifteen to twenty-five minutes to "sull" the rods, i. e., cause the clean, scale free surfaces of the rods to become slightly oxidized.

At the completion of the "sulling" operation, the bundles are removed from the pin and are transferred, one by one, to a vat containing a solution of calcium hydroxid, a lime solution preferably being used.

The bundles of rods are dipped into the calcium hydroxid solution to neutralize any remaining free acid on the rods and to apply a coating of calcium hydroxid to the surfaces of the rods, this coating forming a lubricant carrier thereon which is of advantage in the subsequent wire drawing operations.

The rods, which are still coiled in bundles, are then conveyed to a drying house, and are placed in drying ovens where they are dried or baked at a temperature high enough to drive off the water in the coating and any occluded hydrogen, and harden the coating of calcium hydroxid on the surfaces of the rods.

The bundles are then removed from the drying ovens and are transferred to the draw bench or blocks in readiness to be drawn down into wire.

Each bundle is then uncoiled and as uncoiled is drawn through a die on the draw bench in the usual known manner, and as drawn is again coiled into a bundle, the rod or wire being formed into a coil or bundle after each drawing operation.

In as far as I am aware, it is the universal practice in all commercial wire drawing operations to first pickle, then wash, then "sull," then dry, and then coat the rods, in preparation for the wire drawing operations, while the rods are in bundles, and to again coil the wire after each drawing operation in preparation for a later drawing operation.

It will be obvious that when a series of rods in the form of coils or bundles are immersed in an acid pickling solution that the rods will be over-pickled in the more exposed portions of the bundles, while the less exposed portions thereof will not be effectively scaled or cleaned, and that in afterward washing the adhering acid solution from the pickled bundles, the less exposed portions of the rods may retain some acid thereon, causing "acid brittleness" and later preventing the less exposed portions of

the surfaces of the rods from being uniformly "sulled" and covered with the lime coating.

It also will be readily apparent that to handle each bundle, either manually or mechanically, before and after the successive steps of this old method involves many handlings, requires much labor, and causes great expense in the transforming of rods into wire.

- 10 One object of my invention is the provision of a novel method of cleaning and drawing wire rods into wire, wherein the necessity of bundling the rods or wire and of handling and conveying the rods or wire 75
15 while in bundles from the commencement of the scale removing operation until the completion of the drawing operation or operations, is entirely avoided and overcome.

Another object of this invention is to provide an improved method of removing the scale and cleaning the rods preparatory to the wire drawing operation, wherein "acid brittleness" is prevented, a uniformly cleaned surface is obtained, and the formation of 80
20 "smut" on the materials being cleaned is overcome, and whereby the time required for cleaning the rods is materially lessened and a better product is obtained.

A further object of the invention is the provision of a continuous method of cleaning and drawing wire, wherein the successive steps in the cleaning and drawing operations are simultaneously carried out on different portions of a given length of the 85
30 wire or rods.

A still further object of the invention is to provide an improved method of making wire wherein the rods are continuously cleaned and drawn into wire, and whereby 90
40 the bundles of "green" rods, after being placed on the reels without cleaning, are successively scaled and cleaned, coated and drawn into wire without intermediate bundling, handling, or lifting operations, the labor necessary in making the wire greatly 100
45 reduced, and a material reduction in the cost of cleaning and drawing rods into wire is effected.

These and other objects and advantages 105
50 will be more fully brought out and explained in the following description and appended claims, and illustrated in the accompanying drawings forming part of this specification, in which—

55 Figure 1 is a side elevation, partly in section, of a portion of one arrangement of apparatus adapted for use in carrying out the method forming my invention.

Figure 2 is a similar side elevation, partly in section, of other portions of the apparatus.

By connecting the line X—X of Figure 1, with the line X—X of Figure 2 a complete side elevation of the apparatus will be had.

65 In the accompanying drawings, the letter

A designates a spool or reel for holding a bundle of the uncleared rods at the rear of a mechanical scale remover B, comprising a frame 2 having a plurality of horizontal sheave wheels or rollers 3, and a second 70 plurality of vertical sheave wheels or rollers 4 journaled thereon.

A series of troughs C, D, E, and F are disposed successively forward of and in line with the mechanical scale remover B, each 75 being of substantially the same construction, with the exception that preferably the trough C is of much greater length than the other troughs D, E, and F.

Each trough comprises a rectangular body portion 6 supported on a stand 7 and having an anti-friction bearing roller 8 journaled in suitable bearings at each end of the troughs to support the rods as they pass into and out of the troughs. Either one or more rollers 9 are journaled within the troughs intermediate their ends and spaced from the bottom thereof, and the rods are adapted to pass thereunder so as to be held submerged in the liquid within the troughs. 80
85

The trough C contains a heated solution of sulfuric, muriatic or other acid, which serves to clean off or remove any small particles of scale remaining on the rods after they pass through the mechanical scale remover. The trough D contains hot water for washing the pickled rods so as to remove any free acid on the rods. 90
95

The trough E is a "sull" trough and contains a suitable sull mixture which is heated and which becomes deposited on the rods in passing the rods through the "sull" in this trough. This trough is not necessarily used when drawing wire through the hole of one die block, but is essential when continuously drawing through the holes of more than one die block. The trough F is a coating trough and contains preferably a heated solution of lime which forms a lubricant carrying coating on the rods and also neutralizes the effect of any remaining acid on the rods. If desired, the "sull" and lime coating troughs may be combined, in which case a single trough containing a combined solution of "sull" and lime, or other lubricant carrier 100
105
110

115 will be used.

It will be understood and especially noted that other acids and other coatings may be used, and that this invention is not limited to those specified above.

120 A draw bench having a drawing block G is disposed forward of the trough F, and, desirably, is spaced a considerable distance therefrom so as to permit the lime coating to dry on the rods before they reach the draw bench and are drawn. If found necessary or desirable, an artificial drying box X may be mounted in the space between the trough F and G, to more thoroughly dry 125
130 the rods.

The bench G comprises a frame 10 having a plurality of die boxes 11 mounted thereon, through which the rods are successively drawn to reduce them to the desired size 5 wire.

Forward of each die box is a wire block 12 which is keyed or otherwise rigidly secured on a driven shaft 13 journaled in the frame 10. Each of the blocks, with the exception 10 of the last block, has a suitable pressure roller 15 mounted on a crank arm 15', these rollers being pivoted on the frame 10 and being adapted to bear against a portion of the convolutions of wire on the block to hold 15 said convolutions taut. The rod, as drawn through the die, is wrapped on the block and held by the pressure roller 15. When the space under the roller becomes filled, each additional convolution will force out a 20 convolution from under the roller and allow it to hang loosely on the block. The wire from the loose convolutions or coils is then passed or drawn through the next succeeding die and coiled on a block in a similar manner, and this performance is repeated until 25 the last die is reached, when the wire is wrapped on a take-up block which does not have the pressure rollers, but wraps all of the wire tightly on the block. Each succeeding drawing block is rotated at a greater 30 speed than its preceding block to take up as near as possible the added length of wire caused by drawing. However, any variations in length are compensated for by the 35 loose coils or convolutions on the block preceding the drawing die. This structure and method of drawing wire through several blocks will not be gone into further, since it is made the subject matter of my co-pending 40 application Serial No. 433,283, filed December 27, 1920.

When only a single block and die is to be used, as when the wire is given but a single draft, only the foremost block or take-up block will be used, in such case being mounted on the shaft immediately forward 45 of the first die.

This invention is not limited to any number of drafts, and the rods may be drawn 50 through one or more dies as desired, although when it is desired to pass the rods through more than one draft it is essential that the sull coating be used prior to or in combination with the lime. The method as carried out in accordance with this invention, 55 is as follows—

The rods to be cleaned and drawn are delivered to the rear end of the apparatus, and a bundle, or bundles thereof are mounted 60 on the reel A, then unwound and a single strand thereof threaded over and under (not around) the sheaves 3 and 4 of the mechanical scale remover B, then passing over the rollers 8 and under the rollers 9 of each successive trough so that it will pass through 65

the ingredients in each, and lastly, be drawn through the dies and connected to the block of the drawing bench.

As the block rotates, the rod will be pulled through the mechanical scale breaker B, 70 which will break off all or practically all scale by working or kinking the rods horizontally and vertically. The so scaled rod then passes through the acid trough C which will remove any traces of remaining scale, 75 and then through the hot water trough D to wash off any free acid adhering to the rod, then through the "sull" coating trough E, wherein the rod will receive a deposit of "sull," thence through the lime solution 80 trough F, wherein any free acid remaining on the rod will be neutralized, and a lime coating deposited thereon. After passing through the lime trough F, the rod passes through a considerable open space to dry 85 the coating of lime, and then passes through either one or more of the drawing dies, on the drawing bench G.

If it is desired to only draw the rod through one die, i. e., a single draft, the 90 "sulling" may be omitted, and the rod run over the trough E, and through the trough F, or if a combined "sull" and lime bath is used, the trough F may be omitted and the rod run directly to the drawing bench G, 95 where a suitable lubricant would be applied.

The rods are drawn at a considerable speed and, therefore, remain in each trough only a fractional part of a minute, thereby 100 reducing the time of cleaning and preparing the rods from a number of hours to less than a minute. This reduction in time is made possible due to the fact that the scale is mechanically removed and all intermediate handling, transporting, baking, etc., is eliminated. 105

The rods are in better condition for drawing since the whole surface of each rod is evenly cleaned, and a uniform coating is deposited on the cleaned surface. 110

Acid brittleness, a common defect in the old method of cleaning rods, and which, by the long immersion of the rods in the acid pickling bath caused occluded hydrogen to be produced in the metal, is eliminated under the present method, since the rods are in the acid bath for but a fraction of a minute, and each portion of the length of the rod is in the bath for the same time interval. 115

Owing to the short time the rods are immersed in the acid bath in my improved method, no smut or carbon deposit is formed thereon, while with the old method of cleaning heretofore used, the long immersion in 120 the acid necessary to sufficiently clean the rods of scale, also drew out a certain amount of the carbon from the metal, forming a gritty sooty smut or carbon deposit, which, when the rods were being drawn, cut the 130

dies, caused breaks in the rods being drawn, and retarded the drawing operations.

The present method entirely avoids the disadvantages of the old and cumbersome cleaning method universally used heretofore, removes the necessity for a drying house, and eliminates the heavy manual labor required in lifting the bundles of rods between the successive steps of the method heretofore used.

Under the present method the rods are delivered in bundles to the apparatus shown in the drawings as received from the rod mill in which they are rolled, and are then uncoiled and passed continuously through the cleaning mechanism and different baths and drawn through one or more dies and formed into wire without any intermediate handling or delays in the continuity of the steps of the method.

In carrying out my invention, all portions of the rods are uniformly treated, since the bundles or rolls of rods are uncoiled and passed in a single strand through the cleaning mechanism and baths.

From the above it will readily be understood and apparent that this invention provides a method of continuously cleaning and drawing wire without intermediate

handling or conveying the rods from the time they are delivered from the rolling mill for cleaning until after the finished product is produced.

I claim:—

1. In the manufacture of wire from bundled rods, the method which consists in gradually uncoiling the bundled rods and subjecting the sequentially uncoiled portions thereof, successively, to scale removing, pickling and coating operations, prior to the drawing operation, and then subjecting the coated rods to at least one cold drawing operation.

2. In the manufacture of wire from bundled rods, the method which consists in gradually uncoiling the bundled rods and subjecting the sequentially uncoiled portions thereof, successively, to mechanical scale removing, pickling, washing, sulling, coating and drying operations, prior to the drawing operation, then subjecting the coated rods to at least one cold drawing operation, and simultaneously operating on different portions of the rods in said series of operations.

In testimony whereof I have hereunto signed my name.

ERNST BOLEY.
